BUCKLE

Roy S. Sanford, Oakville, Conn., assignor to The Autoyre Company, Incorporated, Oakville, Conn., a corporation of Connecticut

Application October 8, 1937, Serial No. 167,916

11 Claims. (Cl. 24—73)

This invention relates to a buckle and has special reference to a buckle adapted to be adjustably associated with straps, bands, and the like, for the support of garments or other objects on the person.

More particularly, this invention relates to a loop buckle comprising a member having a cross bar connected between a pair of arms and a second member movably mounted on the arms of the first member including a pair of prongs movable between a position against and a position spaced from the cross bar as the members are moved relatively, there being means on the cross bar for locking the ends of the prongs thereagainst to prevent casual relative movement of the members.

It is contemplated by the present invention to adopt this construction for use with straps, bands, belts, and the like, for the support of various types of objects particularly on the person. However, in the drawing and in the following description the buckle will be shown and described in connection with the shoulder strap and bib of an overall, the strap being threaded through the cooperating members of the buckle in a desired manner. It is readily apparent, of course, that various other uses could be mentioned in connection with buckles and fasteners generally of the type adapted to be adjustably associated with straps and that this invention therefore is not to be limited to the specific use herein described and illustrated.

In a buckle of the above noted type, it is highly desirable to provide for the utmost simplicity and ease of operation in threading the strap through the cooperating members. When the strap is threaded through the cooperating members the end of the strap hangs straight down and behind the bib of the overall to avoid an unsightly appearance and to prevent accidents which might result in the strap end hanging loosely.

It is further contemplated by the present invention to lock the ends of the prongs against the cross bar and in so locking the ends of the prongs to enclose the same, which in the first instance prevents casual relative movement of the members, and in the latter instance guards against accidental misuse of the prongs. When the prongs have pierced the material of the strap and have been locked in place under the projecting ears of the cross bar, the buckle cannot under ordinary circumstances become unlocked unless manually released in the manner hereafter described. Overalls are washed in commercial laundries and it is highly desirable that it be unnecessary to remove the buckles for this purpose, and also, since the buckles are not removed, that they be locked in a manner so as not to become lost in the process of laundering.

Since the prongs must necessarily penetrate the material of the strap in order to hold the strap in various positions of adjustment, the prongs are comparatively sharp. In ordinary use, in the usual type of buckle, these relatively sharp prongs are liable to cause injury to the wearer since tension is not always obtained on the strap in positions of movement of the body and therefore the prongs are not held firmly against the cross bar and may be permitted to lie in a spaced relation therewith, pointing outwardly to catch on objects with which they might come in contact.

The present invention satisfactorily overcomes the above objections in providing an effective lock to prevent loss in the laundering of the garment or during disuse of the garment by the wearer, and also effectively encloses the sharp prongs so that there is no liability whatsoever of engaging any portion of an object with which the buckle might come in contact.

One of the objects of the present invention is to provide a buckle of the type above noted which is comparatively inexpensive to manufacture, is simple and efficient in operation, and is durable.

Another object of this invention is to provide a buckle of the character indicated above wherein the prongs of one of the members thereof are locked against the cross bar of the other member to prevent loss in laundering or in disuse of the garment.

A further object of this invention is to provide a buckle of the hereinabove described character wherein the sharp prongs of one of the members thereof are releasably enclosed to prevent injury to the wearer or to the objects with which the buckle contacts.

Other objects and advantages will hereinafter be more particularly pointed out, and for a more complete understanding of the characteristic features of this invention reference may now be had to the following description when taken together with the accompanying drawing, in which latter:

Figure 1 is a front elevational view of a buckle incorporating the features of this invention, showing its relation with a fragmentary portion of a strap in full lines and the bib of an overall in dotted lines;

Fig. 2 is an enlarged front elevational view of one of the members of the buckle incorporating the features of this invention, showing an initial stage in the manufacture thereof;

Fig. 3 is an enlarged sectional view taken on the line 3—3 of Fig. 2;

Fig. 4 is a view similar to Fig. 3 of the buckle in a completed state of manufacture; and

Fig. 5 is an enlarged elevational view of the buckle shown in Fig. 1 with the strap omitted.

therefrom, and showing a dotted changed position of the prongs thereof.

Referring now more particularly to the drawing, the buckle of this invention comprises a member 10 having a cross bar 11, and a pair of arms 12 and 13 having pivot loops 14 and 15, respectively. The member 10 is preferably formed from a single piece of round wire initially of uniform diameter and subsequently 10 preferably flattened in portions to obtain a desired rigidity and pleasing appearance. An intermediate portion of the wire strip forms the cross bar 11 and the ends are bent at right angles thereto and inwardly toward each other in a 15 spaced relation with the cross bar 11 to form a substantially rectangular slot 16, the extreme ends being bent again at right angles outwardly and into the loops 14 and 15.

A second member 17 is pivotally mounted in the member 11 in the loops 14 and 15, the second member preferably being formed of a single continuous piece of round wire of smaller diameter than the diameter of the wire of the first member 10. An intermediate portion of the 20 wire is formed into a button-receiving loop 18, the entrance to the loop being of lesser width than the diameter of the loop to prevent accidental disengagement of the button from the button-receiving loop.

30 Portions of the wire adjacent to the loop 18 are bent in a direction away from each other and are thereafter directed inwardly toward each other to form loops 19, the width between the loops being sufficiently wide to permit the entrance of a strap 30. Portions 20 and 21 of the 35 wire of the member 17 extending from the loops 19 are formed substantially parallel with the cross bar 11 to be received in the loops 14 and 15 respectively, these portions 20 and 21 being 40 slidably in the loops in the direction of the axes thereof.

Prongs 22 and 23 are preferably formed integrally with and extend substantially at right angles to the portions 20 and 21 respectively of the member 17 in a direction toward the cross bar 11, the ends of the prongs being movable between a position against and a position spaced from the cross bar 11 as the members 10 and 17 are pivoted relatively. Since the prongs 22 and 23 must ordinarily penetrate through the 45 material of the strap, belt, or the like, that is, where openings are not provided in the straps, it is desirable for these prongs to be pointed and sharp.

50 In order to lock the ends of the prongs 22 and 23 against the cross bar 11 to prevent casual relative movement of the members 10 and 17 and to guard against accidental misuse of the sharp prongs, the cross bar 11 is provided with 55 a locking means for releasably enclosing the pointed ends of the prongs. Such locking means are shown in the drawing as ears 24 and 25 which are preferably formed integrally with or are otherwise secured to the cross bar 11.

60 Referring more particularly to Fig. 2 of the drawing, the cross bar 11 is shown as being flattened at the portions 26 and 27 with the material thereof being displaced to provide a seat against which the prongs rest in a normal position of use. Portions of the material of the cross bar 11 adjacent the seats 26 and 27 are further flattened to form the ears 24 and 25 which are 65 preferably substantially narrower than the width of the seats 26 and 27 which, when the ears are bent over, present pockets, the ears extending 70

75 in a spaced substantially parallel relation with the flattened portions or seats 26 and 27. The width of the ears, being narrower than the seats, forms notches 28 and 29 for permitting entry of the prongs into the pockets beneath the ears, 5 the thickness of the normal cross section of the cross bar 11 being preferably substantially as great as the overall cross section at the ears.

The illustration of Fig. 5 in full lines shows the prongs 22 and 23 locked in position against 10 the cross bar 11 by the ears 24 and 25 which are preferably formed integrally therewith. When it is desired to release the prongs from their locked position, loop portions 19 of the frame 17 are urged in a direction of movement 15 toward each other so that the ends of the prongs may be aligned with the notches 28 and 29 adjacent the ears 24 and 25 as shown in dotted lines, and the member 17 may thereafter be pivoted in the loops 14 and 15 so that the prongs 20 may be moved to a position spaced from the cross bar. This movement of the prongs is permissible by reason of the member 17 being resilient, the frame being made of comparatively light wire having a substantially wide loop for 25 receiving the button of the bib of the overall.

The strap 30 of an overall may be inserted through the opening 16 when the prongs are spaced from the cross bar 11, whereafter the prongs pierce the shoulder strap and the end of 30 the strap is directed through the second member between the loops 19 therein to fall downwardly behind the bib 31 of the overall. After the strap has been pierced by the prongs the member 17 is pivoted in a direction such that the prongs 35 move toward the cross bar. During this movement the loop portions 19 of the member 17 are moved toward each other in the direction of the axes of the loops so that the prongs 22 and 23 are in alignment respectively with the notches 30 28 and 29 opening into the pockets formed by the ears 24 and 25.

The movement of the prongs 22 and 23 inwardly toward each other may be limited so as to predetermine the position of the prongs with 45 respect to the notches by means of angular bends 32 and 33 adjacent the portions 20 and 21 respectively of the member 17. After the ends of the prongs 22 and 23 are received in the notches, pressure is released from the loops 19 and the prongs return to an initial normal position of use by reason of the resiliency of the member 17.

While but a single embodiment of this invention is herein shown and described, it is to be understood that various modifications thereof may be apparent to those skilled in the art without departing from the spirit and scope of this invention and therefore the same is only to be limited by the scope of the prior art and the 60 appended claims.

1. claim:

1. In a buckle, a member comprising a cross bar connected between a pair of arms, a second member movably mounted on the arms of said first member and including a pair of prongs movable between a position against and a position spaced from said cross bar as the members are moved relatively, and means on said cross bar for locking the ends of said prongs thereagainst to 70 prevent casual relative movement of said members, said locking means having an overall thickness not exceeding the thickness of said cross bar.

2. In a buckle, a member comprising a cross 75

- bar and a pair of arms, a second member pivotally mounted on the arms of said first member and including a pair of prongs movable between a position against and a position spaced from said cross bar as the members are pivoted relatively, and means on said cross bar for locking the ends of said prongs thereagainst to prevent casual relative movement of said members, said locking means having an overall thickness not exceeding 10 the thickness of said cross bar.
3. In a buckle, a member comprising a cross bar and a pair of arms having pivot loops, a second member pivotally mounted on said first member in said loops and including a pair of prongs movable between a position against and a position spaced from said cross bar as the members are pivoted relatively, and means on said cross bar for locking the ends of said prongs thereagainst to prevent casual relative movement 15 of said members, said locking means having an overall thickness not exceeding the thickness of said cross bar.
4. In a buckle, a member comprising a cross bar and a pair of arms having pivot loops, a second member pivotally mounted on said first member in said loops and including a pair of prongs movable between a position against and a position spaced from said cross bar as the members are pivoted relatively, and means on said cross bar for releasably enclosing the ends of said prongs to prevent casual relative movement of said members and to guard against accidental misuse of said prongs, said enclosing means having an overall thickness not exceeding the thickness 25 of said cross bar.
5. In a buckle, a member comprising a cross bar and a pair of arms having pivot loops, a second member pivotally mounted on said first member in said loops and including a pair of prongs movable between a position against and a position spaced from said cross bar as the members are pivoted relatively, and ears secured to and extending in a spaced substantially parallel relation with said cross bar for releasably enclosing the ends of said prongs to prevent casual relative movement of said members and to guard against accidental misuse of said prongs, said spaced ears lying within the confines of the outer planes of 30 said cross bar.
6. In a buckle, a member comprising a cross bar having flattened portions and a pair of arms having pivot loops, a second member pivotally mounted on said first member in said loops and including a pair of prongs movable between a position against and a position spaced from said flattened portions of said cross bar as the members are pivoted relatively, and ears secured to and extending in a spaced substantially parallel relation with the flattened portions of said cross bar to form 35 pockets for releasably enclosing the ends of said prongs to prevent casual relative movement of said members and to guard against accidental misuse of said prongs, the overall depth of said pockets not exceeding the width of said cross bar.
7. In a buckle, a member comprising a cross bar having flattened portions and a pair of arms having pivot loops, a second member pivotally mounted on said first member in said loops and including a pair of prongs movable between a position against and a position spaced from said flattened portions of said cross bar as the members are pivoted relatively, and ears formed integrally and extending in a spaced substantially parallel relation with the flattened portions of 40 said cross bar to form pockets for releasably enclosing the ends of said prongs thereagainst to prevent casual relative movement of said members, said locking means having an overall thickness not exceeding the width of said cross bar.
8. In a buckle, a member comprising a cross bar having spaced flattened portions of reduced cross section and a pair of arms having pivot loops, a second member pivotally mounted on said first member in said loops and slidable in the direction of the axes thereof, said second member including a pair of prongs movable between a position against and a position spaced from said flattened portions of said cross bar as the members are pivoted relatively, and ears formed integrally and extending in a spaced substantially parallel relation with the flattened portions of reduced cross section of said cross bar for enclosing the ends of said prongs to prevent casual relative movement of said members and to guard against accidental misuse of said prongs, said prongs being releasable upon movement thereof in a direction axially of said loops to a position outside of the confines of said ears. 45
9. In a buckle, a member comprising a cross bar having spaced flattened portions of reduced cross section and a pair of arms having pivot loops, a resilient member pivotally mounted on said first member in said loops and slidable in the direction of the axes thereof, said resilient member including a pair of prongs movable between a position against and a position spaced from said flattened portions of said cross bar as the members are pivoted relatively, and slotted ears formed integrally and extending to form a pocket with the flattened portions of reduced cross section of said cross bar for enclosing the ends of said prongs in a normal position of use to prevent casual relative movement of said members and to guard against accidental misuse of said prongs, said prongs being releasable upon movement thereof in a direction axially of said loops into alignment with the slots of said ears. 50
10. In a buckle, a member comprising a cross bar and a pair of arms having pivot loops, a second member pivotally mounted on said first member in said loops and slidable in the direction of the axes thereof, said second member including a pair of prongs movable between a position against and a position spaced from said cross bar as the members are pivoted relatively, and means on said cross bar for locking the ends of said prongs thereagainst to prevent casual relative movement of said members, said prongs being releasable upon movement thereof in a direction axially of said loops to a position outside of the confines of said locking means, the width of said locking means not exceeding the width of said cross bar. 55
11. In a buckle, a member comprising a cross bar and a pair of arms having pivot loops, a resilient member pivotally mounted on said first member in said loops, said resilient member including a pair of prongs extending from a loop portion and movable in a direction toward and away from each other, said prongs being also movable between a position against and a position spaced from said cross bar as the members are pivoted relatively, and pockets on said cross bar for receiving the ends of said prongs, said prongs being insertable into said pockets through notches adjacent thereto to which said prongs are aligned by a movement thereof toward each other. 60
